GAS WASHING APPARATUS

Alfred R. Earl, Toledo, Ohio

Application August 25, 1945, Serial No. 612,676

1 Claim. (Cl. 261—24)

1

This invention relates to an apparatus for washing gases in which gases are periodically drawn into and expelled from the washer by the operation of liquid piston pumps. It may be used for treating producer gas, for cooling, precipitating solids, for rectification purposes, or for any other purpose where an intimate contact of a liquid with a gas is required.

In the drawings:

Figure 1 is a plan view of one embodiment of the invention using twin units so arranged that in one unit the gases are being drawn in to the washer, while in the other unit the gases are being washed and expelled therefrom.

Figure 2 is a diagrammatic view of the controls, the position of the controls being at the position opposite to that shown in Figure 1.

Figure 3 is a side view from the left of one pair of units.

Figure 4 is a detailed view of the gas intake control valve, showing the same in closed position.

Figure 5 is an elevation of the pulsation tank, with a part broken away to show the float and guide in sections.

As best shown in Figure 1, the apparatus consists of four tanks operating as two pairs of units. Each unit consists of a pumping tank 1 and a washing tank 4, connected by a conduit 2; the arrangement being such that, by periodically applying and releasing pressure in tank 1, a body of liquid in the tank will be lowered and raised, thus forcing the liquid level to simultaneously be raised and lowered in the washing tank 4, as liquid passes from tank to tank through conduit 2. The liquid thus acts as a hydraulic piston to draw in gases during the lowering period and to expel and wash them during the rising period. By a system of controls, later to be described, two units being in pairs, one washer tank is inhaling and the other is exhaling.

The duct 2 enters a bottom opening 3 of a second vertical axis washing tank 4 (Figure 3). Under the practice adopted herein, it is proposed to have the tanks 1, 4, in the range of 10 ft. in diameter, and the connecting duct or conduit 2 about 2 ft. in diameter. The upward pitch or inclination of the duct 2 is shown as about 25°. For the hydraulic piston, there is volume of liquid, as water 5, such that, with the connecting duct 2 filled and the upper liquid level in the tank 4 not quite to its bottom, the tank 1 should be nearly full.

There is a throat or restriction 6, centered by a spider 7 at the bottom opening 3 from the tank 4.

2

During the lowering of the liquid level in the tank 4, this throat 6 acts as a nozzle. Inasmuch as the spider 7 is not fixed in the opening 3, the action is that the throat 6 is lifted sufficiently to permit relatively free back flow of water 5 from the tank 1 through the duct 2 into the tank 4 through the opening 3. As this flow to the tank 4 lessens or stops, the spider 7 and the throat 6 settle back to nozzle position.

10 A breathing chamber 8, into which new gas is drawn and from which it is expelled by the action of the liquid piston, is in tank 4 above the liquid 5. The tank 4 has a partition 9 with a central port 10 to the chamber 8. A poppet valve 11 is upwardly movable to close the port 10.

15 The arrangement is such that gas is drawn in through valves 11 and expelled through perforations in partitions 9 upon which partitions 9 a liquid level is maintained.

20 To actuate the liquid piston, air under pressure from compressor 14, is supplied to header 15 connected to both tanks through branches 16, which extend to valve chambers 17. The lower side of chambers 17 have ports 18 opening into a connecting pipe 13 and into the top of the tanks 1.

25 In a branch duct 19 from the header 15 is a valve 20 to control compressed air flow from the compressor 14 to a chest 21 for a slide valve 22 (Figures 1, 2). With the valve chambers 17 for

30 adjacent tanks 1 aligned, a common piston rod 23 may extend therebetween and have fixed on said rod 23 at the region of the chest 21, a piston in the housing 24. Also fixed with the rod 23, one at each chamber 17, is a piston valve 25

35 adapted to be moved across the port 18. With the valve 25 opening the port 18 for communication with the branch 16 (Figure 2 at the left) the valve 25 at the port 18 is in its extreme position at the right and opens the tank 1 pipe 13 for

40 communication through the port 18 with a branch 26 of a header 27 (Figure 1). The header 27 is connected to a main 28 having a valve 29 therein. It is to be noted that the valve 25, connecting the branch 16 to the tank 1, cuts off the tank 1 from

45 communication with the branch 26 in the showing at the left of Figure 2. Conversely, in the showing at the right of Figure 2, the valve 25, as in position to connect the tank 1 at the right with the branch 26, cuts off communication to this tank 1 from the branch 16. This out-flow of air from the right hand tank 1 (Figure 2) allows the

50 hydraulic piston to act from gravity for in-flow of liquid from its companion tank 4 (Figure 1 at the right). This means that as the chamber 12 in

the tank 4 is of less volume, the chamber 8 above the hydraulic piston in the tank 4 is increased.

Operation of the inlet and exhaust valves described above is effected as follows: At the top of each chamber 4 a float 30 is arranged in guide 33. To the float is attached a vertical rod 31 whose descent is cushioned by a spring 32. Fixed to rod 31 is an arm attached to fixed collar 34 whose free end is linked with a pivoted L-shaped lever 35. The other arm of the L operates a valve 22 through the push rod 36 and valve stem 37. Valve 22 controls flow of pressure fluid to the piston in housing 24 to move the rod 23 to left or right, thereby admitting compressed air to one tank 4 while permitting exhaust from the other. It is thus apparent that the liquid 5, constituting the piston, will be raised and lowered in the opposite tanks 4 at periodic intervals.

Considering now the tanks 4, where the gas washing occurs, provision is made for manipulating the poppet valve 11 in synchronism with the rise and fall of the liquid in the corresponding pumping tank. This is accomplished as follows: Centrally downward to the port 10 in the tank 4 is a duct 39 having a gas supply branch 40 (Figures 1, 3) thereto from a header 41 of producer gas. A stem 42 from the valve 11 (Figures 3, 4) extends through packing 43. Connected to the stem 42 is a counterweight 44 for approximating a balanced condition for the valve 11 and its connected parts. Upon energizing of an electromagnet 45, the valve 11 is closed at the port 10. Sudden throwing of the valve 11 is damped by a dashpot 46, adjusted by an inlet valve 47, with further cushioning by a helical compression spring 46' about the rod 42. The dashpot 46 has an adjustable outlet valve 48 to control or slow down opening of the valve 10.

Electromagnets 45 are energized by closing of switches 50, which in turn are closed by operating arms 51 attached to rod 23. Helical springs 52 urge the switches to open position, and they are closed by pressure of arms 51. As seen in Figure 1, closing of left hand switch 50 completes a circuit from line 49, through left switch 50, line 53, right hand magnet 45, to line 54. On reverse movement, left hand switch 50 opens, while at the right hand end the other switch 50 will be closed and a circuit completed from line 49, through the closed switch 50 to a line 53 extending to the left hand magnet 45, and from this magnet to line 54. Thus the poppet valves are arranged to open when the liquid is falling and to close when the liquid is rising in each of tanks 4.

The chamber 8, in which the liquid 5 is rising toward the closed valve 11, builds up a pressure in this chamber. Ball check valve ports 55 are in the partition 9 from the chamber 8 outward from the port 10. The tank 4, upward from the partition 9, has a chamber 56. A liquid, as water 57, provides a level in this chamber 56 submerging the check valves 55 through which valves the gas, under pressure in the chamber 8, may bubble into the chamber 56. Besides washing the gas as bubbling into the chamber 56, the liquid 57 may have discharge through jets 58 in the duct 39 just above the closed valve 11. With the valve 11 closed, there is thus a shallow pool in the lower portion of the duct 39. With the valve 11

open, this pool is spilled into the chamber 8 with the inrushing raw gas, while the washing action is supplemented by flow from the jets 58.

Liquid to be treated is supplied from a duct 5 67 (Figure 1), to branches 68, which, as shown in Figure 3, deliver to central funnel member 69. The gases, after bubbling through this body of liquid above the partition 9, are drawn off through a duct 67 to a header 66.

10 In cases of gases to be washed, this washing function is thus accomplished by the bubbling action, and replenished through the supply pipes 68.

15 In case the liquid is to be fractionated, provision is made for drawing off the heavier fractions through a line 61 and the lighter fractions through a line 63. The heavier liquid may flow through ports 59 into ring chamber 60, from which it is drawn off through the line 61. The lighter 20 fractions accumulate near the surface of the liquid body and over flow into a pan 62, from which they are drawn off by line 63.

25 Liquid for the hydraulic piston is supplied through a line 73, reducing valve 14, branch line 75 and check valves 76 by the tanks 4.

Heavier particles which may be washed from the gases and get into the lower portion of tanks 4, may be drawn off from the lower end of the bend in conduit 2 through pipes 71 controlled by valves 72.

What is claimed and it is desired to secure by Letters Patent is:

In a gas treating device, a pair of interconnected gas treating units, each unit comprising 35 a pumping tank and a washing tank, a conduit connecting the lower ends of said tanks, said conduit and the lower portion of said tanks being adapted to contain a body of liquid, means to periodically supply and later exhaust a pressure gas 40 to and from the top of said pumping tank to force said liquid to rise and fall as a hydraulic piston in said washing tank; a horizontal perforate partition in said washing tank with means to allow gases to pass upwardly therethrough but 45 prevent liquid from flowing downwardly, means for a gas to be supplied to the space beneath said partition and for a liquid to be supplied above the same as a pool, and valve means so coordinated with said pressure gas supply and exhaust 50 means, that gas is drawn in to one unit at the same time it is being expelled and washed in the other unit by bubbling through said pool.
